UNITED STATES PATENT OFFICE

138,417

DESIGN FOR AN IMPACT WRENCH UNIT OR THE LIKE

Clifford E. Fitch, Bryan, Ohio, assignor to The
Aro Equipment Corporation, Bryan, Ohio, a
corporation of Ohio

Application November 3, 1943, Serial No. 111,579

Term of patent 14 years

(Cl. D54—14)

To all whom it may concern:

Be it known that I, Clifford E. Fitch, a citizen of the United States and a resident of Bryan, in the county of Williams and State of Ohio, have invented a new, original, and ornamental Design for an Impact Wrench Unit or the like, of which the following is a specification, reference being had to the accompanying drawing, forming a part thereof.

Figure 1 is a plan view of an impact wrench unit or the like, embodying my new design.

Figure 2 is a side elevational view thereof.

Figure 3 is a front elevational view of the impact wrench unit; and

Figure 4 is a fragmentary rear elevational view of substantially the left half of the device shown in Figures 1, 2 and 3, the other side being substantially the same.

I claim:

The ornamental design for an impact wrench unit or the like, substantially as shown and described.

CLIFFORD E. FITCH.
